John Schlesinger
ATTORNEY

Patented Oct. 2, 1928.

UNITED STATES PATENT OFFICE.

IKE SCHLESINGER, OF EAST ORANGE, NEW JERSEY.

KNITTED CAP.

Application filed January 21, 1927. Serial No. 162,462.

This invention relates to caps and particularly to those of the knitted type.

An object of this invention is to provide a cap having a neck or rear portion which can be readily and effectively folded up and fastened by the incorporation in a practical manner of hookless fastening means.

Another object of this invention is to provide a knitted cap of generally improved construction which is particularly adapted for durable wear, cheap to manufacture, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a perspective view of my novel cap in position on a wearer's head with the rear band unfolded and secured beneath the chin of the wearer.

Fig. 2 is a perspective view of the cap showing the rear band secured about the crown portion of the same.

Fig. 3 is a perspective view of the cap with the band hookless fastening device in open position, parts being broken away to show the construction of the crown.

Figs. 4 and 5 are enlarged detail views of portions of the locking device and cooperating portions of the cap.

Referring now more specifically to the drawings, I show an embodiment of the invention applied to a cap which preferably is made of a knitted fabric, and comprises a crown C and a band B surrounding the same, said band having a neck or rear portion 12, and a front portion 13. The rear band portion is arranged to be suitably movable with respect to the crown of the cap, and both of the band portions are fastened to the rim of the crown along seam 14.

Said band B is preferably knitted in continuous tubular form, and is then cut as desired to form the band portions aforesaid. Preferably a narrow strip of material is removed along the line of the cut as at 15,

leaving, however, a connecting portion 16 integrally uniting the band portions 12 and 13 at the lower edge of said band, for a purpose to be disclosed hereinafter.

The adjacent edges 12^a and 13^a of the band portions 12 and 13, respectively, at each side of the cap are preferably angularly disposed, and slope from a central side portion of the cap upward and forward with respect thereto. The rear band portion is thus provided with suitable gradually narrowing ends or flaps 12^b adapted to be conveniently secured beneath the wearer's chin by suitable fastening means such as a button 17 engaging in a buttonhole 18.

Engaging means are provided interconnecting the adjoining edges 12^a and 13^a of said rear and front band portions when the rear band portion is folded against the crown of the cap. Said means comprises a hookless fastening device 19 incorporated preferably in the cut 15 of the band structure along the edges 12^a and 13^a of said band portions, so as to bridge the space formed by said cut 15 between the edges 12^a and 13^a. The hookless fastening device is secured to the band portions by tape members 20, which form a pleasing trimming effect, and are secured in place by a cover stitch 21. The stop 22 provided on each hookless fastener device to limit the opening movement of closure slide 23 is positioned and concealed beneath the connecting portion 16. Said slide 23 is preferably provided with a button 24 instead of the usual dangling finger-piece which may be of an ornamental nature and whereby the slide 23 is manipulated in the usual manner. The button conceals the slide and thus improves the general appearance of the cap. The

button on said slider presents a smooth non-irritating surface against the wearer's head when in the position shown in Fig. 1. The front band portion 13 may be formed with the end edges 13^a curving gradually into the upper edge of said band portion beginning at each side thereof substantially at a line at right angles to the hookless fastener and passing through an end 25 of the rear band portions, as shown at 26. The front band portion 13 may be secured to the crown of the cap by anchor stitches 27, the edge portions at 13^a being free.

The crown C is preferably made of a double thickness, and includes an outer layer 11^a and an inner or lining layer 11^b. How-

ever, the band B is preferably made of a single layer of material, whereby a neat and relatively inexpensive cap is produced. Said band may be knitted with a rack-stitched 5 facing and is jersey rib-stitched on the side thereof that normally lies against the crown of the cap. The band portion 12 will consequently show the rib stitches when in use as in Fig. 1. The rib stitches extend length- 10 wise of the band B and provide a rugged resilient structure for withstanding any strains to which the rear band portion may normally be subjected. The rack-stitched facing of the band provides a suitable contrasting trimming effect for the cap. It is to be noted, likewise, that the hookless fastener device including the tape members 20 form a reinforcement for those portions of the rear or neck band portion 12 where 15 the tension is greatest, as when said band portion is used as shown in Fig. 1, and that the slide members 23 serve as connecting anchorage in this position.

It will thus be seen that there is provided 20 a device in which the several objects of this invention are achieved, and which is well adapted to meet the conditions of practical use.

As various possible embodiments might 25 be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

- 10 1. In a cap, the combination of a crown member, a band extending thereabout, said band being cut, and means including a hookless fastener to secure edge portions of said cut for retaining the band in position on the crown member, a portion of said band being movable into desired predetermined position when said fastener is opened.
- 15 2. In a cap, the combination of a crown member, a separate band of uniform width formed of a tubular member and attached to extend completely around said member, said band being cut at the sides of the cap along lines extending from the central side portion of the cap upward and forward to form front and rear band portions, the latter being unfoldable to engage the chin of the wearer, and hookless fastener means for releasably securing together edge portions of said cut.
- 20 3. In a cap, the combination of a crown member, front and rear band portions extending therealong, and locking means at the sides of the cap to secure the band portions together including hookless fasteners disposed along lines beginning at the central

side portions of the cap and sloping upward and forward.

4. In a cap, the combination of a crown member, a band formed of a knitted tubular member surrounding the crown member and cut to form front and rear band portions, and a hookless fastener to join said band portions, the rear band being movable when the fastener is open to engage the chin of the wearer. 70

5. In a cap, the combination of a crown member, a band extending thereabout, the band being cut to provide front and rear portions, the lower end of the cut being spaced from the lower edge of the band to provide an integral connecting portion between said band portions, and a hookless fastener for securing the band portions together including a slide having a stop positioned for concealment beneath said connecting portion. 80

6. In a cap, the combination of a crown member, a band of tubular form extending snugly therearound, the band being cut to provide front and rear band portions, the lower end of the cut being spaced from the lower edge of the band to provide an integral connecting portion for the band portions, a narrow strip of material being removed along the cut to provide an opening, 90 and a hookless fastener joining adjacent ends of the band portion for bridging said opening, said fastener having a slider, a stop for said slider disposed in a concealed position under the connecting portion. 95

7. In a cap formed of knitted fabric, the combination of a crown member formed of two layers of material, a band extending around the crown member formed of a single layer of material, said band being cut at 105 an angle to form front and rear portions, and a hookless fastener engaging adjacent edges of the band portions.

8. In a cap, the combination of a crown member, a band extending therealong, and 110 means to lock the band in position including a hookless fastener having a slide, and a button, said button and a portion of said band being movable to contact with the wearer's face when said fastener is released secured 115 to the slide for manipulating the sliding movement thereof.

9. In a knitted cap, the combination of a crown member, a band extending therealong, and cut to form a band portion movable for 120 engagement with the wearer's chin, and a hookless fastener to secure the band portion in normal position against the crown member, said fastener including tapes for securing said fastener to the band portions, said 125 tapes extending beyond the fastener to form a binding for the edge portions of the cut and to serve as an ornamental trimming.

10. In a knitted cap, the combination of a crown member, a band extending normally 130

therealong and having a portion movable to engage the wearer's chin, and a hookless fastener including tapes to secure the fastener to said band, said hookless fastener serving to support the band portion in its normal position along the crown member and also to reinforce the band portions upon the release of said fasteners when positioning the rear band to cover the wearer's chin, the hookless fastener having a slide member which in the latter position serves as an anchorage to reinforce the band structure at its junction with the cap. ¹⁰

In testimony whereof I affix my signature.

IKE SCHLESINGER.
